UNITED STATES PATENT OFFICE.

CHARLES V. JAMESON, OF CHICAGO, ILLINOIS.

VALVE FOR PLAYER-PIANOS.

1,081,533.

Specification of Letters Patent.

Patented Dec. 16, 1913.

Application filed September 2, 1911. Serial No. 647,356.

To all whom it may concern:

Be it known that I, CHARLES V. JAMESON, a citizen of the United States of America, and a resident of Chicago, county of Cook, 5 and State of Illinois, have invented certain new and useful Improvements in Valves for Player-Pianos, of which the following is a specification.

My invention relates to valves for player 10 pianos and has for its object improvements in such valves and their associated parts.

In the accompanying drawings—Figure 1 is a section on the broken line 1—1 of Fig. 2, and shows the valve and associated parts; 15 Fig. 2 is a plan, partly broken away, of a portion of the vacuum chest and connected parts; Fig. 3 is a section on line 3—3 of Fig. 2; and Fig. 4 is a detail.

In the said drawings A represents the interior space of a vacuum chest, the bottom and sides of which are of wood, while the top is composed of a metal plate B having ports C therein. A tube D connects the space A with a suitable pump for maintaining the 25 desired degree of vacuum.

In the bottom A¹ of the vacuum chest is a recess E having its top closed by a diaphragm or "pouch" E¹. Connected with the recess E is an air channel F which communicates, by means of a rubber tube G, with a port in the tracker bar of the player. A branch F¹ (Fig. 3) of the channel F connects said channel with the vacuum chest A. This branch is closed by a plate F² which 30 has a minute hole in its center so that the actual communication between the chest A and the recess E is that afforded by this small hole in plate F². The plate B has a valve seat around each port C, and valves H 35 on stems H¹, close these ports. These valves have rubber or leather faces as shown. On the lower ends of the stem H¹ are adjustable heads H² which rest on the diaphragm E¹. Secured to the metal plate B is a metal cap 40 K having a port K¹ adapted to be closed by the upper face of the valve H when that valve is in its upper position. When the valve is in its lower position it closes the port C. The metal around the port K¹ is 45 bent inward as shown to form a seat for the valve H. Over the port K¹ is a bridge K² having a central pin K³ which enters a hole in the stem H¹ for the purpose of guiding the valve H. This hole has a felt or other 50 soft bushing H³ as shown in Fig. 4. This is

for the purpose of avoiding metallic contact in moving parts.

Secured to the vacuum chest A¹, and in association with each valve H, is a pneumatic P which is connected to some one of 60 the striking actions of the piano. This pneumatic is connected with the interior of the cap K by a passageway P¹.

The tracker bar is a bar or plate having perforations or ports therein, each one of 65 the ports being connected by a rubber tube G with the space under a corresponding diaphragm E¹; and also, through the branch channel F¹ and hole F² with the interior of the vacuum chest A. A perforated sheet of 70 paper representing music is caused to move over the ports of the tracker bar at a desired speed. As long as the paper covers a particular port in the tracker bar, the air in the pneumatic tube G, and in the space E under 75 the diaphragm E¹ will be withdrawn through the opening F² so that the same degree of vacuum will exist in these spaces as that which exists in the chest A. In this condition the valve H closes the port C, and 80 outside air enters the port K¹ and flows through the passageway P¹ to the pneumatic P.

When a perforation in the paper coincides with a port in the tracker bar, air will flow 85 through the connected tube G to the corresponding recess E, and the difference in air pressure on the two sides of the diaphragm E¹ will cause that diaphragm to rise. This movement of the diaphragm moves the valve 90 H so as to open the port C and close the port K¹. In this condition the inside of the pneumatic P is in direct communication with the vacuum chest A with the result that the pneumatic collapses and causes an operation 95 of a corresponding piano action. When the moving paper again closes the port in the tracker bar, the air in the tube G and the recess E will be withdrawn through the small opening F. This leaves greater air 100 pressure on the top of the valve H than exists under the diaphragm E¹ with the result that the valve is shifted so as to open the port K¹ and close the port C. In this condition outside air flows through the port 105 K¹, the interior of the cap K and the passageway P¹ to the pneumatic P. This permits the parts to return to original position as shown in the drawings.

It has heretofore been the practice to make 110

the vacuum chest, valves and connected parts, entirely of wood or entirely of metal. Wood is preferable in that it is cheaper and easier to handle. Wood is disadvantageous 5 by reason of being partially pervious to air and being subject to atmospheric variations which cause warping, splitting, swelling, contracting, etc. This is particularly objectionable in valve seats and in the thinner 10 parts of the chest. Metal is preferable in that it can be made air tight and the valve seats can be kept in proper condition. Metal is objectionable because it is more expensive than wood and also because it is 15 not desirable to have metal in a piano in a form in which it can possibly act as a sounding board.

It will be observed in the preceding description that I have combined wood and 20 metal in such a form as to obtain the advantages of both and the objections of neither. The main and heavy parts of the chest are

made of wood while the valve seats are in a metal plate which binds the wooden parts together and tends to prevent them from warping and splitting. The removable caps K are made in a form which permits an easy and rapid flow of air to and from the pneumatics, and being individual for each valve they provide easy access thereto. 25 30

What I claim is:—

A valve, upper and lower seats therefor, an elongated axial opening in the stem of the valve, a felt or other soft bushing in said opening, and a fixed pin adapted to 35 enter said bushing and fit therein so as to guide said valve.

Signed at Chicago, Ill. this 29th day of August 1911.

CHARLES V. JAMESON.
